F. WEINBERG.

VACUUM FEED APPARATUS,
APPLICATION FILED MAR. 8, 1916.

1,325,180.

Patented Dec. 16, 1919.

UNITED STATES PATENT OFFICE.

FREDERICK WEINBERG, OF DETROIT, MICHIGAN.

VACUUM FEED APPARATUS.

1,325,180.

Specification of Letters Patent. Patented Dec. 16, 1919.

Application filed March 8, 1916. Serial No. 82,870.

To all whom it may concern:

Be it known that I, FREDERICK WEINBERG, a citizen of the United States, residing at Detroit, county of Wayne, State of Michigan, have invented a certain new and useful Improvement in Vacuum Feed Apparatus, and declare the following to be a full, clear, and exact description of the same, such as will enable others skilled in the art 10 to which it pertains to make and use the same, reference being had to the accompanying drawings, which form a part of this specification.

My invention relates to vacuum feed apparatus for internal combustion engines and an object of my improvements is to provide a more perfect apparatus for this purpose that may be easily assembled and cheaply constructed and which will operate at low 15 speeds of the engine with the throttle valve open and with engines of high volumetric efficiency.

I accomplish this object in the device illustrated in the accompanying drawings in 20 which this invention is shown in connection with an apparatus disclosed in part in my copending application Serial Number 61,535 filed November 15, 1915.

Figure 1 is a sectional view of an apparatus embodying my invention.

Fig. 2 is a sectional detail view of part of said apparatus.

Fig. 3 is a sectional view of a modified form of a portion of the apparatus.

15 *a* is the auxiliary tank consisting of the vacuum chamber *b* and the reservoir *c*. *k* is the supply tank, and *m* is a conduit by which gasolene passes from the tank *k* to the vacuum chamber *b*. *d* is a float in the vacuum chamber *b*.

20 *e* is a metal disk forming a dividing partition between the chamber *b* and reservoir *c*. The shells or inclosing walls of the chamber *b* and reservoir *c* are of thin bell-shaped metal having flanges at their open ends, which flanges are secured upon opposite sides of the disk *e*.

25 *h* is the equalizing tube. This is flanged at its end as shown at *i* and passes through an aperture *j* in the flange of the bell-shaped inclosing wall of the chamber *b*. The flange *i* is clamped between said flange and the disk *e* with interposed packing, the bore of the pipe *h* registering with an aperture *g* in

said disk which communicates with the 55 groove *f* communicating with the reservoir *c*. *x* is a conduit joining the chamber *b* and reservoir *c* and passing through a central aperture in the disk *e*. Said conduit is provided with a shoulder *x*³ which engages 60 against the under surface of the disk *e* and the upper end of said conduit is spun over upon the upper surface of the disk *e* as shown in Fig. 1 at *x*² so as to secure said conduit in position.

65 *n* is a plug closing an aperture in the lower end of the bell-shaped inclosing wall of the reservoir *c*. This plug is supplied with a shoulder *n* fitting against the lower surface of the wall of the reservoir and it is 70 spun over as shown at *n*² to clamp against the upper surface of said wall and secure the plug in position.

75 *o* is a conduit leading from the reservoir *c* to the carbureter *o*². *o*³ is the intake pipe to an internal combustion engine communicating in any usual way with the carbureter *o*². *p* is a throttle valve in the intake pipe *o*³. *q* is a part of the combustion chamber of the engine and *q*² is the intake valve. *r* 80 is a pipe communicating with the combustion chamber *q* and terminating in a nozzle *s* having a very small aperture therethrough, such for instance as would be formed by a number 55 drill.

85 *v* is a vacuum producing passage consisting of a pipe communicating with the chamber *b* and with the intake passage *o*³ between the throttle valve *p* and the intake valve *q*². *t* is an ejector nozzle forming the 90 communicating passage between the pipe *v* and the intake pipe *o*³. The nozzle *s* opens into a contracted portion of the nozzle *t* axially in line therewith as shown in Figs. 1 and 3. *v*² is an automatic valve between 95 the chamber *b* and the ejector nozzle *t*. *u* is the plug of a cock adapted to open and close the communication between the pipe *r* and nozzle *s*. *u*² is a lever by which the plug *u* may be turned. *p*² is a lever by which the 100 throttle valve *p* may be turned. *p*³ is a connecting rod between the levers *u*² and *p*². By this connection when the throttle valve *p* is open the passage between the pipe *r* and the nozzle *s* is also open and when the throttle valve is partly closed, the connection between said pipe and nozzle is closed.

This cock and plug *u* as well as valve *v*²

may be omitted, as shown in the modification of Fig. 3.

Obviously this device will operate to produce the vacuum even if it is not connected 5 to the intake pipe.

w is a plug closing an aperture in the upper portion of the inclosing bell-shaped wall of the chamber b. w² is a chamber in said plug in which is placed a strainer w³. The 10 chamber w² communicates by a drilled passage w⁴ with the vacuum chamber b and the supply conduit m communicates with the chamber w², so that the supply of gasoline passes from the conduit m through the 15 strainer w³ and the passage w⁴ to the vacuum chamber b.

5 is a deflecting plate extending over the float d. This plate has grooves 7 in it with which grooves the passage w⁴ communicates, 20 thus the gasoline supplied to the chamber b is carried beyond the float d and does not fall upon said float. The deflecting plate 5 is secured in place by a nut 10 screwed upon the threaded shank of the plug w to 25 secure the latter in place.

2 and 3 are parallel legs of a U-shaped wire united by a loop 9. The leg 2 acts to displace the valve to open the equalizing passage h and upon the leg 3 is placed a 30 valve 4 adapted to close the vacuum producing passage. 8 is a loop extending in a plane at right angles to the loop 9 and inclosing the latter. The loop 8 is rigidly connected to the float d and is of such a 35 size as to allow considerable lost motion between itself and the loop 9.

w⁵ is a passage extending from grooves 7 to an opening covered by plug w⁶. This plug may be removed at will leaving an 40 opening through which the apparatus may be primed when required.

The operation of the above described device is as follows:

When the float d rises it contacts the loop 45 9 first contacting the valve in the equalizing passage then the float submerges to an increased extent, then it forces said valve from its seat, and then rising further brings the valve 4 up against its seat closing the 50 vacuum producing passage. When the liquid is drawn from the chamber b the float d falls until the upper part of the loop 8 engages the loop 9 and upon a further dropping of the level of the sustaining 55 liquid the weight of the float d draws the valve 4 from its seat and opens the vacuum producing passage.

In starting up the engine, the vacuum created in the intake manifold at nearly 60 closed throttle, will create a vacuum in the suction passage v, and subsequently in the vacuum chamber b, and fluid will be drawn from the main tank k, through the liquid conduit m, over the strainer w³ and passage 65 w⁴. With the opening of throttle p, the

vacuum decreases rapidly, and to such an extent that it would not raise the fluid high enough for the height that comes in question in the modern vehicles. This is especially the case when the engine is climbing a hill on high gear, with wide open throttle, low engine speed and a very low located main tank. However it will be seen that with the opening of the throttle the 70 ejector nozzle s is brought into communication through the passage r with the explosion chamber q and consequently the explosion gas from the engine will escape through the ejector and create a secondary suction entirely independent from the static 80 depression in the intake manifold, in the pipe v, and vacuum chamber b. It is then this new vacuum which draws the fluid from main tank k through conduit m, into chamber b. As shown in Fig. 3, the nozzle may 85 be located in the exhaust manifold o^{3a} in which case it is entirely the ejector action of the nozzle that is being depended upon for raising the fuel.

In all these cases the action of the medium 90 surrounding the nozzle whether it is exhaust gases or air movement due to the moving vehicle supports and increases the ejector action.

It will be observed that the plug n and 95 the conduit x may be very cheaply and efficiently secured in place in the construction shown and that the wire having parallel legs 2 and 3 united by the loop 9 with the engaging loop rigid with the float d may 100 be cheaply constructed and forms an easily assembled apparatus. The same holds good for the fastening of the equalizing tube h. The chamber w² may be cheaply and conveniently formed in the plug w and the 105 strainer w³ is located in a conveniently accessible place.

v is a bracket having the form of a portion of a cylinder with an inturned flange at its upper end. The bracket is secured in 110 place by the same bolts that secure the parts of the tank and the disk e together. This bracket serves for a means for securing the tank to its support. The shape of the bracket makes it strong and rigid even when 115 made of light metal.

What I claim is:

1. In a vacuum feed apparatus, the combination of a vacuum chamber, an apparatus actuated by the vacuum therein and operated therewith to elevate a liquid, a vacuum producing passage communicating with said chamber, an internal combustion engine adapted to be supplied from said apparatus, an ejector adapted to produce a vacuum in 120 said passage, and means incident to the operation of the engine for actuating said ejector.

2. The combination of a vacuum chamber and apparatus actuated by the vacuum there- 130

in, and operative therewith, to elevate a liquid, a vacuum producing passage, and an ejector adapted to produce a vacuum in said passage, an internal combustion engine having a cylinder, said ejector being connected with the cylinder of the engine so that said ejector shall be operated by gases supplied from said cylinder.

3. The combination of a vacuum chamber 10 and apparatus actuated by the vacuum therein, and operative therewith, to elevate a liquid, a vacuum producing passage communicating with said vacuum chamber, and an ejector adapted to produce a vacuum in 15 said passage, an internal combustion engine having a cylinder, an intake pipe to said cylinder, a throttle in said intake pipe, said ejector communicating with said intake pipe between said throttle and said cylinder.

20 4. The combination of a vacuum chamber and apparatus actuated by the vacuum therein, and operative therewith, to elevate a liquid, a vacuum producing passage communicating with said vacuum chamber, and 25 an ejector adapted to produce a vacuum in said passage, an internal combustion engine having a cylinder, said ejector being connected with the cylinder of the engine so that said ejector shall be operated by gases supplied from said cylinder, said ejector communicating with the intake pipe to said cylinder.

30 5. In a vacuum feed apparatus, an operating float, a loop connected with and extending from said float, and a valve operating part consisting of a wire bent to form two parallel portions with a loop joining the same, the loop rising from said float engaging over the loop joining said parallel portions and said parallel portions extending and reciprocating in guides.

35 6. In a vacuum feed apparatus, a dividing wall having an aperture therethrough, a conduit having a shoulder, said conduit passing through said aperture with its shoulder against one surface of said dividing wall, said conduit being spun over upon the other surface of said dividing wall to secure said part in position.

40 7. In an auxiliary tank for vacuum feed apparatus, a disk, bell-shaped parts having flanges around the open ends of said parts, said flanges being secured to said disk, an equalizing pipe having its end provided with 45 a flange, said flange lying under the flange of one of said bell-shaped parts and being secured in position thereby.

8. In a vacuum feed apparatus, the combi-

nation of a main tank, a supplementary tank, a conduit adapted to supply liquid from said main tank to said supplementary tank, said supplementary tank being provided with an upper and a lower chamber, a carbureter, said lower chamber being connected to said carbureter, an internal combustion engine 60 having a cylinder, an ejector, said cylinder being connected to said ejector to operate the same, a vacuum producing passage communicating with said upper chamber, said ejector being adapted to produce a vacuum in 65 said passage, an apparatus actuated by the vacuum in said chamber and operative therewith to elevate the liquid, and means for equalizing the pressure in both chambers when required.

75 9. In a vacuum feed system, a vacuum producing passage, a valve controlling said passage and having its stem formed into a loop, an operating float and a U-shaped projection rising from said float and engaging said loop with lost motion substantially as and for the purpose described.

10. In a supplementary tank for a vacuum feed system, a disk, bell-shaped parts having flanges around the opening end of said parts, said flanges being secured to said disk forming an upper and a lower chamber, an aperture in said lower chamber, a conduit having a shoulder, said conduit passing through said aperture with its shoulder against one surface of said lower chamber, said conduit being spun over upon the other surface to secure said part in position.

80 11. The tank *a*, the bracket *y*, said bracket consisting of a thin plate having the shape 85 of a portion of a cylinder having its axis approximately parallel to that of the tank and being secured at its upper edge to said tank.

90 12. The combination of a vacuum chamber and apparatus actuated by the vacuum therein, and operative therewith, to elevate a liquid, a vacuum producing passage, and an ejector adapted to produce a vacuum in said 95 passage, an internal combustion engine having a cylinder, said ejector being connected with the cylinder of the engine so that said ejector shall be operated by gases supplied from said cylinder, a cock in the connection between the ejector and cylinder, a throttle valve, said cock and throttle valve being connected so as to turn together.

100 In testimony whereof, I sign this specification.

FREDERICK WEINBERG.
